UNITED STATES PATENT OFFICE.

HOWARD A. SLITER, OF LOS ANGELES, CALIFORNIA.

MACHINE FOR MAKING ORNAMENTAL CRUSHED LININGS.

Application filed April 2, 1924. Serial No. 703,833.

This invention is a machine for making ornamental lining such as used in caskets and the like, the lining comprising a silk facing which is uniformly crushed at spaced intervals and in directions at right angles to one another, in order to produce a crinkled effect, the facing having a flat fabric backing fixed thereto at the depressions of the crinkled surface, for maintaining said crinkled effect when the lining is removed from the machine.

As is usual in this type of machine, the present construction consists generally of a series of parallel ribs adapted for limited movement toward and away from one another and having projecting pegs and needles, and a series of rods adapted to be laid one after another across the ribs on the silk facing which is placed on the expanded rib structure, said rods extending across the ribs in parallel spaced relation between the pegs, so as to depress the facing between said pegs and fix the same on the needles, thus crushing the facing transversely of the ribs and at spaced intervals; the ribs being moved towards one another after all of the rods are in place, so as to crush the facing longitudinally of the ribs and at spaced intervals, and thus produce the crinkled effect, the fabric backing being then fixed to the crinkled facing at the protuberances formed by the pegs, with said backing held in place by gluing or sewing, after which the rods are drawn out from between the facing and its backing, and the crinkled lining thus formed is lifted off the needles of the ribs and removed from the machine.

It is the object of the present invention to provide a machine of this character employing but one set of ribs and having the needles and pegs fixed thereto so as to eliminate the necessity for vertical movement of the rib structure, and to arrange the transverse rods so as to depress the facing between the pegs projecting from the ribs, and fix the same on the needles and against the ribs, a construction which leaves the protuberances formed in the silk facing by the pegs, free of needle holes, so that glue cannot pass through said facing and spoil the front of the lining, when the backing is applied to said facing by gluing the latter at said protuberances formed therein.

It is a further object of the invention to provide a construction including a shield adapted to be placed over the crushed facing so as to expose only the protuberances formed therein by the pegs of the rib structure, in order that glue may be applied only to such exposed protuberances when fixing the backing to the crinkled facing.

It is a still further object of the invention to provide means for readily adjusting the limit of expanding movement of the ribs relative to one another, so as to provide for variations in the crinkled design formed by the machine.

The invention will be readily understood from the following description of the accompanying drawings, in which:

Fig. 1 is a plan view of the machine with the ribs expanded, and showing the facing laid thereon, and several of the transverse rods mounted on said facing, for depressing the latter against the ribs between the pegs projecting therefrom, and fixing the depressed portions of said facing on the needles carried by the ribs.

Fig. 2 is a transverse section on the line 2-2 of Fig. 1.

Fig. 3 is a detail section on the line 3-3 of Fig. 2.

Fig. 4 is a plan view of a corner of the machine, showing the facing laid thereon, and the ribs contracted and the rods in place, with the gluing shield mounted over the protuberances formed in the facing by the projecting pegs of the ribs.

The improved machine may be mounted on any suitable support shown as a rectangular frame 1 having transversely spaced cross bars 2. Angle irons extend the length of the frame parallel to one another, with horizontal sides 3 of said angle irons resting upon the frame and cross bars, and vertical sides 4 of said angle irons forming the ribs of the machine.

The angle iron at the transverse center of the frame is preferably bolted thereto as shown at 5, and the remaining angle irons are adapted for limited movement toward and away from one another and said fixed angle iron. As an instance of this arrangement, bolts 6 extend loosely through the ribs 4 of each of the angle irons, the heads 7 of said bolts being adapted to impinge against one side of said ribs, and the threaded ends

8 of said bolts being received through the ribs of the next adjacent angle irons as shown in Fig. 2.

Nuts 9 are threaded on said bolts against opposite sides of the ribs of said next adjacent angle irons, in order to adjustably fix said bolts relative to said next adjacent angle irons, and permit movement of said ribs away from one another until the heads of 10 the bolts abut against the ribs, with the limit of said movement regulated by adjustment of nuts 9.

The ribs may be moved toward one another with the head ends of the bolts sliding 15 through the ribs, until next adjacent angle irons abut, the bolts connecting adjacent ribs being staggered as shown in Fig. 1 so as not to interfere with such contraction of the rib structure.

20 Handles 10 are preferably provided on the outer ribs of the construction at the respective sides of the machine, to facilitate expanding and contracting the mechanism.

Pegs 11, preferably formed integral with 25 ribs 4, project an appreciable distance above the latter, and are equidistantly spaced from one another along each rib, the pegs of one rib being preferably midway between the pegs of the next adjacent rib as clearly 30 shown in Fig. 1.

Needles 12 are mounted in the horizontal sides 3 of the angle irons so as to extend upwardly alongside the ribs 4 of said angle irons, with the points of said needles projecting slightly above said ribs. In the 35 present instance a pair of the needles are mounted between adjacent pegs of each rib, each needle being spaced lengthwise of the ribs an equal distance between adjacent staggered pegs of next adjacent ribs as shown in Fig. 3.

Rods 13, longitudinally grooved at their undersides as shown at 14, and preferably 45 rectangular in cross section and of a length equal to the width of the frame 1, are adapted to be laid across ribs 4 in the spaces between the staggered pegs, thereby positioning the rods over the needles which project above the ribs adjacent each of the pegs, so 50 that said needles may have their points received in the grooves in the rods.

It will be noted that pairs of said rods may be laid across the rib structure between adjacent pegs of a rib, with the staggered 55 pegs of the next adjacent rib between the rods of each pair, and each of said rods overlying a needle of each rib, or in order to vary the crinkled design made by the machine, a single rod may be laid across the 60 rib structure between adjacent pegs of each rib as shown in Fig. 3.

In operation, the ribs being in expanded position, a piece of fabric 15 adapted to form the facing for a lining is spread over 65 the ribs as shown in Fig. 1, and the rods 13

are laid one after another across the rib structure on the fabric, parallel to one another and between the staggered pegs 11, so as to depress the fabric between the pegs and fix the same on the points of needles 12. 70

The ribs 3 are then moved toward one another to contracted position as shown in Fig. 4, thus crushing fabric 15 in usual manner, so that a usual flat fabric backing may be then laid over the crinkled fabric facing and stitched thereto at the protuberances of said fabric facing formed by pegs 11. 75

It will be noted however that the crinkled fabric facing formed as thus described, is 80 free from needle holes at the protuberances in said facing formed by the pegs of the machine, so that the backing for the lining may, if desired, be glued to the facing at such protuberances instead of being stitched thereto as has been the practice heretofore, without the liability of the glue seeping through the facing fabric at such needle holes and spoiling the front of the lining. 85

For this purpose, after the ribs 4 are contracted so as to produce the crinkled effect in the facing fabric, a shield 16 is laid over the crushed goods, said shield being perforated as shown at 17, in alignment with the pegs 11 when the ribs 4 are contracted, so that the ends of the pegs and the protuberances formed in the fabric facing will project through said perforations as shown in Fig. 3. 95

Glue may then be freely applied to the 100 portions of facing 15 projecting through the perforations of the shield, and after removal of said shield, the fabric backing for the lining may be glued to such protruding portions of the facing.

After the backing is fixed to the facing 105 15 of the lining, either by sewing or gluing, the rods 13 are withdrawn transversely from the machine in usual manner, and the lining is lifted from the machine so as to disengage the needles from the facing, and 110 permit removal of the finished product.

It will be apparent that various changes 115 may be made in the construction, combination, and arrangement of parts as thus described, without departing from the spirit of the invention. 115

What is claimed is:

1. A machine of the character described comprising ribs alongside of one another and adapted for transverse movement toward and away from one another, spaced pegs projecting an appreciable distance above said ribs, needles having their points projecting slightly above said ribs between said pegs, and rods grooved at their undersides adapted to be laid across said ribs between said pegs with the projecting points of said needles received in said grooves. 120

2. A machine of the character described comprising a frame, angle irons mounted on

- said frame in parallel relation and adapted for transverse movement toward and away from one another, vertical sides of said angle irons forming ribs having spaced pegs projecting an appreciable distance above the same, needles mounted in horizontal sides of said angle irons adjacent said rib sides and having the points of said needles projecting slightly above said ribs, and rods 10 grooved longitudinally at their undersides adapted to be laid across said ribs between said pegs with the projecting points of said needles received in said grooves.
3. A machine of the character described comprising parallel ribs adapted for transverse movement toward and away from one another, spaced pegs projecting an appreciable distance above said ribs, the pegs of each rib being midway between the pegs of 15 the next adjacent rib, pairs of needles projecting slightly above each of said ribs between next adjacent pegs thereof, each of said needles being spaced midway between a peg of a rib and the adjacent staggered peg of the next adjacent rib, and rods 20 grooved at their undersides adapted to be laid across said ribs between the staggered pegs with the projecting points of the needles received in said grooves.
- 30 4. A machine of the character described comprising parallel ribs, bolts extending loosely through each of said ribs with the heads of said bolts adapted to impinge against one side of said ribs and the threaded ends of said bolts extending through next adjacent ribs, nuts on said bolts at opposite sides of said next adjacent ribs for adjustably fixing said bolts relative to said next adjacent ribs, spaced pegs projecting an appreciable distance above said ribs, needles 35 projecting above said ribs, and rods adapted to be laid across said ribs between said pegs.
5. A machine of the character described comprising ribs alongside of one another, 40 said ribs being adapted for movement toward and away from one another, abutment means for limiting transverse movement of said ribs away from one another, means for adjusting said abutment means 45 to vary the limit of said transverse movement, spaced pegs projecting an appreciable distance above said ribs, needles projecting above said ribs, and rods adapted to be laid 50 across said ribs between said pegs.
- 55 6. A machine of the character described comprising rows of spaced pegs adapted for transverse movement relative to one another, needles between the pegs of said rows, and rods adapted to be laid between said pegs transversely of said rows and over said 60 needles.
7. In a device of the character described, a plurality of angle bars having a vertical web, spaced upstanding portions formed on said vertical web, means for slidably securing said bars one to the other, a plurality of weight members adapted to be positioned on 65 said bars between said upstanding portions, and a plurality of pins positioned along said bars adjacent said vertical webs.
- 70 8. In a device of the character described, a plurality of spaced bars movable toward and from one another, spaced pegs projecting above said bars, a plurality of weight members adapted to be positioned on said 75 bars between said pegs, and pins on said bars between said pegs.
9. In a device of the character described, a plurality of spaced, parallel bars movable toward and from one another, spaced pegs 80 carried by and projecting above said bars, a plurality of weight members adapted to be positioned across the bars between said pegs, and fixed pins on said bars adjacent and between said pegs, said pins projecting from said bars and terminating a distance below the outer ends of said pegs.
- 85 10. In a device of the character described, a plurality of spaced, parallel angle bars having a horizontal web and a vertical web, 90 means for slidably securing said bars together for movement toward and from one another, spaced upstanding portions formed on the vertical webs, a plurality of weight members for mounting in position across 95 said bars between said upstanding portions, and pins mounted on said horizontal webs adjacent the vertical webs between the upstanding portions thereof, said pins extending a distance above the vertical webs of 100 said bars.
11. A machine for ornamenteally crushing a lining, including laterally adjustable support slats, and devices engageable with said slats to variously limit spacing adjustment 105 of said slats.
12. A machine for ornamenteally crushing a lining, comprising, adjustable slats having stitch locating elements in staggered relation, and means for varying the extent 110 of opening adjustment of said slats to change the form of crush imparted to the lining.
- In testimony whereof I have affixed my signature to this specification.
